UNITED STATES PATENT OFFICE.

MALCOLM B. MOYER, OF MONTEVIDEO, MINNESOTA.

STANCHION.

1,188,362.

Specification of Letters Patent. Patented June 20, 1916.

Application filed September 9, 1915. Serial No. 49,741.

To all whom it may concern:

Be it known that I, MALCOLM B. MOYER, a citizen of the United States, residing at Montevideo, in the county of Chippewa and State of Minnesota, have invented certain new and useful Improvements in Stanchions; and I do declare the following to be a full, clear, and exact description of the invention, such as will enable others skilled in the art to which it appertains to make and use the same.

My invention relates to improvements in cattle stanchions and has for its objects to improve upon the general construction of devices of this class to render them extremely simple yet durable, and to provide a novel form of latch for securing the laterally movable side bar of the stanchion in closed position.

With these general objects in view, the invention resides in certain novel features of construction and in unique combinations of parts to be hereinafter fully described and claimed, the descriptive matter being supplemented by the accompanying drawings which constitute a part of the application and in which:

Figure 1 is a side elevation of a stanchion constructed in accordance with my invention showing the movable side bar thereof closed in full lines and open in dotted lines; Fig. 2 is an enlarged section through the upper end of the stanchion; Fig. 3 is a top plan view; Figs. 4 and 5 are vertical transverse sections as viewed on the planes indicated by the lines 4-4 and 5-5 of Fig. 2, and Fig. 6 is a perspective view of the latching lever.

In these drawings, similar reference characters designate corresponding parts throughout the several views, the numeral 1 having reference to an upright relatively fixed side bar preferably constructed of channel iron with its side flanges disposed outwardly. The lower end of the bar 1 is bent laterally as seen at 2 to provide the lower end of the stanchion, while the upper end of said bar 1 is bent in a similar manner as disclosed at 3 to constitute the top of the stanchion and is extended laterally and downwardly in the form of an arm 4, the side flanges of the arm 4 being disposed upwardly as clearly shown in Figs. 4 and 5.

Pivotaly connected at 5 to the lower end 2 of the stanchion by any preferred means, is the laterally movable side bar 6 which is

preferably, though not necessarily, constructed of channel iron. The upper end of the arm 6 carries a guide 7 including a pair of parallel side plates 8 receiving loosely therebetween the arm 4 and projecting above said arm. When the stanchion is in use, the guide 7 is positioned as shown in full lines in Fig. 1, but when the stanchion is standing idle, the guide is disposed at the outer end of the arm 4, this movement as well as the amount of travel of the bar 6, being limited by the head 9 and nut 10 on the opposite ends of a bolt 11 which is passed through the side flanges of the aforesaid arm. This bolt not only serves as stop means for the purpose defined, but coacts with a latch now to be described.

Pivoted adjacent one end upon a bolt or the like 12 which extends transversely through the projecting upper ends of the plates 8, is a latch member 13 here shown in the form of a substantially horizontal lever which is disposed above the arm 4 and provided with a depending rib 14 having one of its ends shaped to form an approximately upright stop shoulder 15 bearing normally against the bolt 11 when the bar 6 is in closed position, the rib being received between the side flanges of the arm 4 as clearly shown in the several figures of the drawings. In order to allow the shoulder 15 to remain in reliable engagement with the bolt 11 when an animal yoked in the stanchion exerts pressure outwardly on the side bar 6, said shoulder is disposed obliquely of the line of thrust between the pivot 12 and the bolt 11, and recedes downwardly from the bolt 12. The portion of the lever 13 disposed on the side of the bolt 12 remote from the shoulder 15, is preferably forked at 16 and is provided with one or more rockers 17 which bear upon the upper edges of the side flanges of the arm 4.

The stanchion is slightly resilient due to its metallic formation, and this resiliency, due to the rockers 17, is applied to use for the purpose of holding the free end of the lever 13 lowered to retain the oblique stop shoulder 15 in tight contact with the stop bolt 11. By so doing, the laterally movable side bar 6 is reliably held in closed position. When, however, said bar is to be shifted to the dotted line position as disclosed in Fig. 1, the free end of the lever 13 is pulled upwardly against the tension exerted by the stanchion frame to such an extent as to

allow the shoulder 15 to clear the aforesaid bolt 11. The bar 6 may then be swung laterally to release the animal previously yoked in the stanchion.

5 When the stanchion is opened, or in other words, when the bar 6 is swung laterally outward, it becomes expedient to provide means whereby said stanchion may be held in such position as to permit the animal to 10 again insert its head therethrough when allowed to enter the stall. For this purpose, the free end of the lever 13 is equipped with a horizontal fork 18 which embraces an upright post 19 when the stanchion is open, 15 if the stalls be of metal construction, whereas an appropriate cleat will be provided in place of the post 19 if the stalls be built of wood. By the provision of the fork 18, the stanchion is held against turning on its 20 supporting chains 20 for the reason set forth, and said fork serves effectively as a handle for operating the lever 13.

A stanchion constructed as above described will be extremely simple and durable, and due to its rigid construction, it may readily withstand the rough usage to which it is subjected when in use, particularly when two animals are endeavoring to occupy the same stanchion to reach the feed 30 trough usually in advance thereof. Upon such an occurrence, the strain is more effectively resisted by the heavy guide 7, the arm 4, and by the forked lever 13, than by other types of construction previously 35 designed for the attainment of the same results. Emphasis is therefore laid upon the general simple construction of the stanchion, but equally upon the specific locking means applied to use by the resiliency of the 40 frame.

From the foregoing, taken in connection with the accompanying drawings, the numerous novel features of construction, the advantages of such features, and the manner 45 of operation of the improved stanchion will be readily apparent. I wish it understood, however, that the exact details shown need not be used since numerous changes may be made within the scope of the invention without departing from or sacrificing 50 any of the advantages thereof.

I claim:

1. A stanchion including a resilient frame having a laterally swinging side bar, and 55 latch means for said bar including a pivotally mounted member having a rocker spaced from its pivot and disposed in contact with a portion of the frame, whereby the resiliency of the latter will serve to normally retain said member in active position.

2. A stanchion including a resilient frame having a laterally swinging side bar, and 60 latch means for said bar including a pivotally mounted member having on one side

of its pivot a shoulder for coaction with a stop on the frame, and having on the other side of its pivot a rocker disposed in contact with a portion of the frame, whereby the resiliency of said frame may serve to retain 76 the aforesaid member in active position.

3. A stanchion comprising a resilient frame including a laterally movable side bar, and a relatively fixed channel shaped transverse arm at the upper end of said bar, 75 a stop in the channel of said arm, and a latching lever pivoted near one end to the upper end of the movable bar, and having on its underside a longitudinal rib received in the channel and having one end disposed on an oblique line receding downwardly from the pivot of the lever to form a shoulder for contact with the aforesaid stop, said lever having at its pivoted end a rocker bearing on the upper 80 side of the arm, whereby the resiliency of the frame will serve to retain said lever in active position.

4. A stanchion comprising a resilient frame including a laterally movable side 90 bar and a relatively fixed transverse arm at the upper end thereof, a stop on said arm, and a latching lever pivoted near one end to the upper end of the movable bar, having on its free end a shoulder bearing against 95 the stop, and having on its other end a rocker bearing on the arm, whereby the resiliency of the frame may serve to retain the aforesaid lever in active position.

5. A stanchion comprising a resilient 100 frame including a laterally movable upright side bar and a relatively fixed transverse arm at the upper end thereof, said arm being channel-shaped in cross section with its side flanges extending upwardly, a stop carried by the arm between said side flanges, a guide rising from the movable bar and surrounding the arm, and a lever pivoted near one end to said guide above the arm, said lever having at its free end a stop shoulder 110 disposed between the side flanges of the arm, in contact with the stop, and having at its other end a rocker bearing on the upper edge of one side flange of the arm, whereby the resiliency of the frame may be exerted 115 to retain the aforesaid lever in active position.

6. A stanchion comprising a resilient frame having a laterally movable side bar, and latch means for said side bar including 120 a latching member held in operative position by the resilient action of the frame.

7. A stanchion comprising a frame including an upright laterally movable side bar, a relatively fixed arm disposed transversely of the upper end of said bar, said arm being channel-shaped in cross section, a guide surrounding the arm and carried by the movable bar, latching means for holding said bar against movement including a mov- 125 130

able member disposed between the flanges of the arm, and a bolt passed transversely through said flanges for coaction with said member, the ends of the bolt being disposed in the outward path of the guide, whereby to serve as stops for limiting the outward movement of said guide and the aforesaid bar.

8. A stanchion for use in comparatively wide stalls, comprising an upright relatively fixed side bar having a laterally projecting arm at its upper end of a length greater than the width of the stanchion proper, a laterally movable side bar having at its upper end a sliding engagement with the inner end portion of the arm and adapted to travel to the outer end of said arm when the stanchion is opened, a stop on said outer end of the arm, and a latching lever extending between the movable bar and the stop and having on its outer end a fork for engagement with a post or the like at one side of the stall when the stanchion is opened, the inner end of said lever being connected to the laterally movable bar, whereby when

said bar is opened to its limit, the lever will project beyond the arm and will position the fork at a point remote from said arm for engagement with the aforesaid post or the like.

9. A stanchion comprising a frame including a laterally movable side bar and a relatively fixed channel-shaped transverse arm at the upper end of said bar, a stop in the channel of said arm, and a latching lever above said arm pivoted near one end to the upper end of the movable bar and having on its under side a longitudinal rib received in the channel, said rib having one end disposed on an oblique line receding downwardly from the pivot of the lever to form a shoulder for contact with the aforesaid stop.

In testimony whereof I have hereunto set my hand in presence of two subscribing witnesses.

MALCOLM B. MOYER.
